UNITED STATES PATENT OFFICE

WALTER C. WILSON, OF MONROVIA, CALIFORNIA

AIR CLEANER

Application filed August 19, 1930. Serial No. 476,280.

This invention relates to a device for cleaning air. More specifically it relates to an air cleaner adapted for use on internal combustion engines.

5 A principal object of the invention is to devise and construct an improved air cleaner having a substantially constant resistance to air flow at the operating ranges of the engine to which it is attached.

10 Another principal object is the provision of an air cleaner in which there is no accumulated air restriction at any given velocity of air flow.

Another object is the provision of an air 15 cleaner in which the air is thoroughly cleaned of all injurious foreign material.

Other objects include an air cleaner which is simple in construction and manufacture, and highly efficient in use and service.

20 With the above and other objects, which will be apparent, the invention consists in the novel construction and relative arrangement of parts, members and features shown in a preferred embodiment in the accompanying drawings, in which:

Figure 1 is a sectional view of the improved air cleaner;

Figure 2 is a sectional view taken on the line 2—2 of Figure 1;

30 Figure 3 is a top plan view on a reduced scale;

Figures 4 and 5 are enlarged sectional views showing a modified construction of the filter retaining walls;

35 Figure 6 is an enlarged detail view, showing a modified construction for transmitting pressure for balancing the liquid columns in the device; and

40 Figure 7 is an enlarged sectional view showing a portion of the wall construction of the cleaner.

The desirability of cleaning air for internal combustion engines, particularly for tractors, where air containing a large amount of injurious material is encountered, has been recognized for some time. One of the difficulties involved in attaching an air cleaner to the carburetor is the resistance to air flow and particularly the variable resistance created by 50 most of the known types of air cleaners.

Applicant has previously designed an air cleaner to overcome these difficulties. The subject-matter of said invention is covered by the United States applications Serial No. 190,532, filed May 11, 1927, and Serial No. 55 282,799, filed June 24, 1928. This invention relates to an improved cleaner embodying the principles of the prior inventions and adapting them to a device more suitable for commercial purposes. 60

In the drawings, a cylindrical casing 1 is provided with a top in the form of a casting 2, which is secured by studs 3 to an annular member 4 secured to the casing 1. The member 4 is provided with an annular groove 5 around the outside thereof, into which the upper edge of the casing 1 is bent to form a tight joint. The member 4 is provided centrally with an annular portion 6 to form a support for an air inlet tube 7, which extends 70 centrally downwardly into the casing. Web portions 8 join the center portion 6 to the outer portion of the member 4. A substantially annular passage-way is formed between the inner and outer portions of the member 75 4.

The casting 2 is bored to form a central passage-way 9 in alignment with the air inlet tube 7. In the usual construction, an air inlet pipe is secured to the casting communicating with the tube 7. The casting 2 is also cored to form an annular passage-way 10 communicating with the passage-way formed in the member 4, and an air outlet passage 11 is also formed extending 85 outwardly from the annular portion 10. The passage-way 11, in the operation of the device, is connected to the air intake of a carburetor by any suitable means, not shown. 90

At the bottom of the cylindrical portion 1 of the casing, a member 12 having substantially the same diameter as the casing is secured thereto by rivets 13. The member 12 is formed to make an air tight fit with the lower portion of the casing. An outwardly projecting bead 14 is rolled in the member 12, and, in the assembly of the device, is adapted to fit against the outwardly extending flange 15 on the bottom of the casing 1. 100

The rivets 13 and additional rivets 16 secure apertured brackets 17 to the casing for a purpose to be hereinafter described.

The member 12 extends downwardly a short distance below the flange 15 with substantially the same diameter as the casing 1. The lower portion from this point is corrugated, as shown in Figure 2, and reduced in diameter. A liquid reservoir 18 having substantially the same diameter as the casing 1 is fitted over the cylindrical portion of the member 12. A rolled bead 19 at the top of the reservoir is adapted to fit against the bead 14. The reservoir is so constructed that an air tight fit is not formed where it contacts with the casing. This construction is so provided that the space or chamber 27' between the upwardly extending wall of the reservoir and the corrugated portion of the member 12 will form an oil seal chamber which is in communication with the atmosphere.

The enlarged wall section of the cleaner shown in Figure 7 illustrates a condition which exists in commercial production of an air cleaner embodying the invention. Due to inaccuracies true cylindrical walls are never formed, with the result that at different locations around the circumference 30 at the top of the reservoir 18 it will be spaced from the cylindrical portion of the member 12. These spaces form the communication between the chamber 27' and the atmosphere. An annular groove 20 is rolled in the reservoir 18 to form an indicator for showing the proper liquid level in the reservoir. Altho various liquids may be used in devices of this type, oil is generally used. Hereinafter the liquid will be referred to as 35 oil. A strip 21, secured to the bottom of the reservoir, extends laterally to each side thereof and is provided with notched portions 22. Clamp rods 23, secured to the brackets 17, extend through the notched portions 22 and are provided with threaded wing nuts 24 for holding the reservoir in position.

As shown in the drawings, the air inlet tube 7 terminates slightly below the normal static level of the liquid in the reservoir, which would be at the groove 20. This is a preferred construction, but it is to be understood that the air inlet tube may terminate adjacent the oil level either below or above. 45 A cylindrical member 25 extends from an intermediate point in the casing downwardly below the normal oil level in the reservoir.

The top of the member 25 may be circular in cross section, as shown in Figure 1. In some constructions it has been found desirable, for reasons which will be described in connection with the operation of the device, to form indentations 36 at the top of 50 the member 25, as shown in Figures 4 and 5.

These indentations may be of any desired shape and number, depending upon the restriction desired.

The member 25 is of such a diameter that it engages the inner portions of the corrugations formed in the member 12, as shown in Figure 2. The member 25 is rigidly secured to said corrugated portions by rivets 37, as shown in Figures 1 and 2. In the modification shown in Figure 6, the rivets 37^a are hollow for transmitting pressure to the air seal chamber, as will be further described in the description of the operation. It will be understood that passage-ways 26 are formed between the member 12 and the member 25 by the corrugations. These passage-ways provide a means of communication between a chamber 27 formed between the casing 1 and the member 25 and the oil reservoir. It will be noted, by an inspection of Figure 1, that the sum total of the area of the passage-ways 26 increases as the corrugations flatten out at the top of the member 12 until the area is the same as the cross sectional area of the passage 27. This construction has a particular function, which will be hereinafter described in detail.

Adjacent the bottom of the member 25, an inwardly extending bead 28 is formed. This bead and a bent-in portion 29 at the bottom of the member provide means for holding an annular bottom member 30 in position. A bottom plate 31 having a centrally located opening 38 is secured by bolts 32 to the annular member 30. In some constructions it 50 has been found desirable to employ a cap 39 mounted on the plate 30 spaced above the opening 38.

A handle or bail 33 is secured to the bottom plate 31 for removing the same when it is found desirable to gain access to the interior of the cleaner for removing chaff or other such material therefrom. It will be noted that the member 25 terminates a substantial distance below the normal static oil 105 level in the reservoir 18, providing a substantial space and liquid chamber between the end of the air inlet tube 7 and the bottom plate 31.

A screen 34 is positioned at the top of the chamber formed between the casing 1 and the air inlet tube 7. This chamber is filled with a filtering material such as steel wool packed against the screen 34 and completely filling the chamber down to the top of the member 25. The filtering material extends downwardly into the chamber formed between the air inlet tube 7 and the cylindrical member 25. Adjacent the bottom of the air inlet tube, an annular screen 35 is placed to hold the filtering material in position. It will be noted that in the construction shown the filtering material terminates above the static liquid level, as indicated by the groove 20.

In the operation of this device, suction is

created at the air outlet passage 11 by attaching the same to the air inlet of a carburetor. Air pressure in the inlet tube 7 pushes the liquid level down until, when a certain pressure differential is reached between the inlet and outlet of the cleaner, air begins to flow around the bottom of the air inlet tube and up through the filtering material, carrying with it a substantial amount of oil. Due to the fact that the filtering material terminates very close to the surface of the liquid, from the beginning of air flow, oil is thrown into the bottom of the filtering material and creates a resistance therein, whereby it is carried up through the filtering material by the air flow. The inlet tube 7 and the member 25 are so spaced that a sufficient resistance is created in the filtering material, due to the liquid therein, to carry the liquid upwardly even at comparatively low rates of air flow through the cleaner. At the top of the member 25, the velocity of the mixture of air and oil is considerably reduced by the large increase in cross sectional area provided at that point. Due to this action, the oil collects into larger drops and flows outwardly and downwardly through the chamber 27 and the passage-ways 26, back into the oil reservoir. The additional filtering material above the top of the member 25 in addition to its filtering action provides means for removing the oil from the air.

In the modification shown in Figures 4 and 5, the indentations 36 in the top of the member 25 form an additional restriction at the top of the filtering material and a decrease in the ratio of the cross sectional area above the top of the member 25 and beyond the discharge thereof. This construction has been found effective to obtain a better separation of the liquid from the mixture of air and liquid passing up through the filtering material.

As the velocity of air flow through the device increases, the oil level at the bottom of the air inlet tube lowers, due to the fact that the oil is carried away faster than it enters through the restricted opening 38 in the plate 31. There are also other forces acting which have a tendency to reduce the amount of oil available to be mixed with the air as the rate of air flow increases.

It will be understood that the liquid in the oil reservoir has three different pressures acting on its surface. Between the reservoir and the member 12 in the chamber 27 atmospheric pressure is acting on a substantial area of the surface. In the passage-ways 26 formed by the corrugations in the member 12, and the member 25, a pressure is acting on the surface which is substantially the same as the outlet pressure of the air cleaner, being somewhat less, due to the resistance in the filtering material between the top of the passage 27 and the outlet. However, as there

is comparatively little oil in this material, the resistance is not great and pressure is substantially that of the outgoing air.

On the central portion of the liquid body, which normally stands above the bottom 31, the pressure is near atmospheric, being somewhat less due to resistances encountered in the air inlet tube and the other means for conducting air thereto. This pressure is transmitted through the opening 38 to the liquid body so long as the liquid remains above the bottom 31.

Due to the possibility of some types of construction of the joint between the reservoir 18 and the member 12 becoming clogged up, it may be desirable to provide other means for communicating atmospheric pressure to the air seal chamber. In the modification shown in Figure 6, the rivets 37^a joining the member 25 to the member 12 are hollow, whereby the pressure on each side of said walls is equalized. By this construction the pressure within the member 25, which, as has previously been stated, is substantially atmospheric, is transmitted to the air seal chamber. It may be found desirable to construct the joint between the reservoir and the casing air tight and to provide a pressure communicating means such as the hollow rivets 37^a.

When a considerable depression is being created at the outlet of the cleaner, this depression is transmitted to the chamber 27 and the passages 26, with the result that the oil level rises in these passages, said passages and said chamber providing in effect a liquid displacement chamber. If the depression becomes sufficient, the oil rises until it reaches the flared out portions of the member 12 at the beginning of the chamber 27. Beyond this point, a comparatively large amount of oil is necessary to fill the large cross sectional area of the chamber 27. This results in a substantial decrease of the oil level in the liquid seal passage between the member 12 and reservoir wall. As the pressure operative upon the opening 38 is substantially atmospheric plus the height of liquid in the liquid seal chamber, the action of depression in chamber 27 lowers the liquid head effective to force liquid through the opening 38 by lowering the level in the liquid seal chamber 27.

Due to this effect, as the depression increases and consequently the rate of air flow through the cleaner increases, less oil is delivered through the opening 38 and up through the filtering material. As the oil mixed with the air forms a substantial part in the resistance of the filtering material, it is evident that, as the rate of air flow increases, proportionately less oil being delivered thereto, the resistance in the filtering material does not increase as would be expected, but, due to the lower ratio of liquid to air, it remains substantially constant. In fact, a device similar to this has been so constructed in which the resistance

is constant over a wide range of air velocities. The value of this is very evident in connection with the use of such devices in internal combustion engines, due to the fact that it is difficult to get proper carburetion with different engine speeds and loads, if the resistance in the air intake varies appreciably.

It is to be understood that the basic principle involved in this device is covered by my 10 co-pending applications. In this application I have shown a preferred embodiment of an improved device having certain novel features which are set forth in the following claims.

15. What is claimed is:

1. An air cleaner comprising a casing closed at the top and open at the bottom, an oil reservoir positioned over the lower portion of said casing in overlapping relationship with respect thereto and spaced therefrom whereby a liquid seal chamber is formed, said chamber being in communication with the atmospheric, an air inlet tube extending into the casing and terminating adjacent the normal static liquid level in the reservoir, a cup-like member positioned at the inner end of the inlet tube, said member having an apertured bottom portion spaced below the end of the inlet tube and upwardly extending walls 25 spaced in part from the tube and from the wall of the casing, filtering material disposed between the inlet tube and the cup-like member walls and between the tube and casing walls, and an air outlet from the top of the casing.

2. A device as set forth in claim 1, in which the bottom portion of the cup-like member extends below the liquid level in the reservoir.

3. A device as set forth in claim 1, in which means is provided for transmitting the pressure in the cup-like member to the liquid seal chamber.

4. A device as set forth in claim 1, in which the inlet tube terminates below the normal static liquid level in the reservoir.

5. A device as set forth in claim 1, in which a restricted centrally disposed opening forms the aperture in the bottom of the cup.

50. 6. A device as set forth in claim 1, in which a cap is positioned over the opening in the bottom of the cup in spaced relation thereto.

7. A device as set forth in claim 1, in which the space between the lower portion of the casing and the upwardly extending walls of the cup-like member varies in cross sectional area in an upward direction.

8. A device as set forth in claim 1, in which the upwardly extending walls of the cup-like member terminate at an intermediate point in the casing whereby the space occupied by the filtering material in the upper portion of the casing has a larger cross sectional area than the space between the inlet tube and the walls of the cup-like member.

9. A device as set forth in claim 1, in which the upwardly extending walls of the cup-like member are shaped at the top to form a restricted passage-way.

10. A device as set forth in claim 1, in which the casing and the reservoir are cylindrical and of substantially the same diameter, the liquid seal chamber between the lower portion of the casing and the overlapping reservoir being formed with a diameter less than the lower portion of the casing.

11. A device as set forth in claim 1, in which the lower portion of the casing is vertically corrugated whereby the inner portions of the corrugations may contact with the upwardly extending walls of the cup-like member, said corrugations forming oil return passage-ways.

12. An air cleaner comprising a casing, air inlet and outlet means to said casing, filtering material positioned in the casing, means associated with the casing for containing a body of liquid, means for delivering liquid from said containing means for passage with the air into the filtering material, the rate of delivery being determined by the pressure in the containing means, means transmitting substantially the pressure at the outlet means to a portion of the surface of the liquid body for displacement of the liquid, a liquid chamber in communication with the liquid containing means below the liquid level therein, and means effective to apply a pressure substantially above the pressure at the outlet means to the liquid in said chamber, whereby the pressure effective to deliver liquid from the liquid body is regulated by the pressures transmitted to the liquid containing means.

13. An air cleaner comprising a casing, air inlet and outlet means to said casing, filtering material positioned in the casing, means associated with the casing for containing a body of liquid, means for delivering liquid from said containing means for passage with the air into the filtering material,

the rate of delivery being determined by the pressure in the containing means, a liquid displacement chamber in communication with the liquid containing means below the liquid level therein, means effective to transmit substantially the pressure at the outlet means to said chamber, a liquid chamber in communication with the liquid containing means below the liquid level therein, and means effective to apply a pressure substantially above the pressure at the outlet means to the liquid in said chamber, whereby the pressure effective to deliver liquid from the liquid body is regulated by the pressures transmitted to the liquid containing means.

14. A device as set forth in claim 13 in which the displacement chamber varies in cross sections taken perpendicular to its vertical dimension, whereby the amount of liq-

uid displaced varies at a rate different than the rate of variation of the pressure at the outlet means.

15. A device as set forth in claim 13, in which the means for transmitting the outlet pressure to the liquid body forms a liquid return passage-way for directing liquid from the filtering material to the liquid body.

In testimony whereof I affix my signature.
